CLAIM

The ornamental design for a game table, as shown and described.

DESCRIPTION

FIG. 1 is a front perspective view of a new design for a game table.

FIG. 2 is a right side view of a new design for a game table.

FIG. 3 is a left side view of a new design for a game table.

FIG. 4 is a front view of a new design for a game table.

FIG. 5 is a rear side view of a new design for a game table.

FIG. 6 is a top view of a new design for a game table; and,

FIG. 7 is a bottom view of a new design for a game table.

The broken line showing is included for the purpose of illustrating portions of the “article” and forms no part of the claimed design. The dash-dot-dot lines represent the boundary of the claimed design.

1 Claim, 7 Drawing Sheets
